RELAY INTERLOCK

George F. Weinreich, Cary, Ill., assignor to C. P. Clare & Company, Chicago, Ill., a corporation of Illinois

Application March 4, 1948, Serial No. 12,949

4 Claims. (Cl. 175—337)

1

The present invention relates to electric relays and is particularly concerned with improved means for causing two relays, in addition to operating electric contacts, to control the relays of one another mechanically.

In accordance with my invention, the two relays may be arranged so that when both relays are energized, they will attract their armatures and thereafter the first relay de-energized will prevent the armature of the other relay from dropping back until the first relay is energized again.

It is the principal purpose of my invention to provide a relay interlock of the character described which exerts no biasing influence on the armature in either position of the armature. My invention contemplates a device of this character wherein the armature of two adjacent relays are provided with arms extending generally parallel to each other, the arms being positioned on opposite sides of a block which has a passage for a freely movable lock means, the arms having depressions therein cooperating with the interlock means to prevent the depressions on the two arms from moving out of alignment with the interlock at the same time.

It is a further object of my invention to provide an interlock device including arms movable with the armature of two adjacent relays with interlock means which are relatively independent of the inaccuracies in spacing or mounting that are found in practice whereby they may be fitted to a particular installation at the time they are installed.

The nature and advantages of my invention will appear more fully from the following description and accompanying drawings illustrating a preferred form of the invention. It should be understood, however, that the drawings and description are illustrative only and should not be considered as limiting the invention except insofar as it is limited by the claims.

In the drawings:

Figure 1 is a plan view of two relays interlocked in accordance with my invention;

Figure 2 is a plan sectional view through the interlocking mechanism;

Figure 3 is a front face view of the relay and the interlocking mechanism;

Figure 4 is a sectional view taken on the line 4—4 of Figure 1;

Figure 5 is an enlarged fragmentary sectional view taken on the line 5—5 of Figure 2; and

Figure 6 is a perspective view of a portion of one of the interlocked bars showing a slightly modified form thereof.

Referring now to the drawings, my invention is illustrated in connection with a two relay installation wherein a mounting bracket 10 mounts two electromagnets 11 and 12 which have pivoted armatures 13 and 14 respectively. The armature 13 has an arm 15 thereon which is adapted to operate a bank 17 of electrical contacts. The armature 14 has an arm 16 for operating a bank 18 of electrical contacts.

10 It is often times desirable in relay installations to have some interlocking means between the relays so that when the armature of either relay is in a certain position, it prevents the armature of the other relay from moving. My invention lies 15 in the provision of a simple and effective means for interlocking the armatures of the two relays. I provide an arm 19 on the armature 13 and an arm 20 on the armature 14. These arms are of nonmagnetic material, and substantially devoid 20 of any spring characteristics. The arms 19 and 20 extend toward the mounting bar 10 and substantially in parallel planes. A block 21 on the frame 10 has a portion 22 extending between the ends of the arms 19 and 20. The block portion 25 22 has a passage 23 through it in a direction transverse to the arms. The arm 19 has a depression 24 therein and the arm 20 has a depression 25 therein. The depressions face the block portion 22 and are so positioned as to align with the passage 23 when the armature is in its attracted position. An interlocking means is transversely movable in the passage 23. This interlocking means, as shown, comprises two balls 26. The overall dimension of the two balls combined 30 is greater than the length of the passage 23 by approximately the depth of one of the depressions 24—25. It is obvious that when one of the depressions 24—25 is aligned with the passage 23, the balls 26 can move in a direction to locate one of them in the depressions, thus allowing the opposite arm to move its depression out of alignment with the passage 23. The ball nearest the opposite arm is permitted to project beyond the portion 22 a few thousandths of an inch to form 40 a small anti-friction guide for the arm.

In Figure 2 the parts are shown with the armature 14 attracted by its electromagnet 12 so that the depression 25 on the arm 20 is positioned to receive the ball 26. This allows the arm 19 to drop if the armature 13 is not attracted by its electromagnet 11. It is evident of course that the reverse condition is also easily provided for, in which case the depressions would be aligned 50 with the passage in the block portion 22 when

the armatures are not attracted by their electromagnets.

The depressions 24 and 25 as shown are elongated lengthwise of the arms 19 and 20. This is particularly important in taking care of variations in mounting and other variable conditions since it makes it possible to have the armature to mounting frame distance vary over a wide range without interfering with the interlock mechanism. It is sometimes found necessary also to bend the arms 19 and 20 up or down in order properly to align them with the passage 23. Since the material of the arms is such that it can be bent readily, the installer of the apparatus can readily take care of this adjustment at the time of installation.

The free ends of the arms 19 and 20 are mounted in position against the sides of the block portion 22 by a keeper 27 which is in the form of a channel strip. It is secured by a screw 28 to the block 21. Preferably it is of a nonmagnetic but somewhat resilient material so that it yieldingly presses the arms inward. Small projections 29 and 30 are pressed in from the sides of the channel 27 to bear on the arms 19 and 20.

In some instances it is desirable to have the relay that is energized first, attract its armature to set up a signal circuit and then open the signal circuit while remaining locked up. This is of course, provided for in the bank of spring contacts. In order to adapt the interlock mechanism to this action, the bar on the armature which sets up the signal circuit is provided with a wider slot or depression 24' as shown in Figure 6. With this wider depression, the armature 13 when attracted, can pull up far enough to set up the signal circuit and then, when the relay is deenergized, drop back to break the signal circuit with the slot 24' still in alignment with the interlocking means 26. The armature will therefore remain latched up by the interlock means until the other armature is attracted to bring the arm 20 into position to align its depression 25 with the interlock means 26.

It is believed that the nature and advantages of my invention will be clear from the foregoing description. Having thus described my invention I claim:

1. An attachment for a pair of electro-magnets each having an armature, comprising an arm mounted on each armature, the arms having portions adjacent to their free ends arranged side by side in spaced relation, a stationary block between said portions said portions being supported by their respective arms and the armatures for pivotal swinging movement in substantially parallel planes across the adjacent faces of said block, said block having a transverse passage between said portions, ball means in the passage of greater overall length than the distance between the adjacent arm portions, said arm portions having seats therein for the ball means, the seats comprising grooves in the side faces of the arms elongated lengthwise of the arms.

2. An attachment for a pair of electro-magnets each having an armature, comprising an arm mounted on each armature, the arms having portions adjacent to their free ends arranged side by side in spaced relation, a stationary block between said portions, said block having a transverse passage between said portions, ball means

in the passage of greater overall length than the distance between the adjacent arm portions, said arm portions having seats therein for the ball means, the seats comprising grooves in the side faces of the arms elongated lengthwise of the arms, one of said grooves being substantially wider than the ball portion seated therein providing limited movement of the arm while interlocked.

3. An attachment for a pair of electromagnets each having a pivoted armature comprising, adjustable parallel arms made from bendable, non-magnetic material, said arms being fixedly attached to said armatures at one end to swing with the armatures, an interlocking means provided at the opposite end of said arms, said interlocking means composed of a block spacing said arms apart and having a transverse slot and balls in said slot engaging and locking one of the said arms by means of recesses in said arms, one of said recesses being wider than the other and each recess being shaped as a channel extending lengthwise of the arm in each of said arms, and said particularly shaped recesses providing an interlocking means for said arms to prevent both arms from rotating about their pivot points from a position where the arm recess is aligned with the slot in the block at the same time.

4. An attachment for a pair of electromagnets each having a pivoted armature comprising, adjustable parallel arms made from bendable, non-magnetic material, said arms being fixedly attached to said armatures at one end to swing with the armatures, an interlocking means provided at the opposite end of said arms, said interlocking means composed of a block spacing said arms apart and having a transverse slot and balls in said slot engaging and locking one of the said arms by means of recesses in said arms, one of said recesses being wider than the other and each recess being shaped as a channel extending lengthwise of the arm in each of said arms, said particularly shaped recesses providing an interlocking means for said arms to prevent both arms from simultaneously rotating about their pivot points away from the position where their recesses align with the slot in the block, and a resilient channel shaped member fixed to the said block springingly urging said arms against said spacing block while said arms move in a plane perpendicular to the longitudinal axis of said slot in said spacing block.

GEORGE F. WEINREICH.
